OVERHEAD DOOR LOCKING MECHANISM

Christ Buehner, Milwaukee, Wis., assignor to
Phenix Manufacturing Company, Inc., Milwaukee, Wis., a corporation of Wisconsin

Application October 11, 1944, Serial No. 558,247

5 Claims. (Cl. 292—177)

This invention relates to improvements in overhead door locking mechanisms.

The invention is particularly, although not solely, concerned with locking mechanism for an overhead door of the type which includes two or more superimposed and foldably connected sections arranged relative to tracks or guiding means in a manner so that rollers or bearings carried by the margins of the door ride in said tracks, and those carried by the top section of the door are on supports which may project outwardly or collapse relative to the door section, whereby, for the elevation of the door, a path utilizing but a minimum of head room is required.

In conventional doors of the type under consideration, due to the low elevation of the overhead portion of the guiding track for the door, the upper section of the door may usually break or fold inwardly upon initiation of slight movement of the entire door, with the result that unless the door is locked in its lowered position in a manner eliminating play, the upper section of the door might be unauthorizedly worked or pushed inwardly to permit access to the interior of the building. With the foregoing in mind, it is therefore, one of the objects of the present invention to provide a locking mechanism for an overhead door which will prevent any play or slight vertical movement of the door when it is in its locked, closed position, whereby the upper panel may not be pushed inwardly.

A further object of the invention is to provide, in an overhead door, locking and latching mechanism which is easily operated from exteriorly of the door by the simple manipulation of a push button or plunger.

A further object of the invention is to provide, in an overhead door, combination lock and latch mechanism which necessitates, on the exterior of the door, a minimum of projecting hardware, thereby economizing in the head room required for the door when it is in its overhead position.

A further object of the invention is to provide an overhead garage door locking mechanism wherein the shaft for one of the door guiding rollers serves as a housing for a reciprocatable locking rod.

Certain types of overhead garage door locking mechanisms which utilize projectable shafts for locking engagement with a portion of a guiding track, or the like, are so arranged that a tamperer may operate the locking mechanism regardless of the position of the door with the result

that if the door is partially open and the locking rod is projected, it may engage adjacent an exterior portion of the track with the result that when the door is then lowered, the offset surface of the track will react eccentrically against the projected locking rod and pry certain hardware loose from the door. The aforementioned difficulty is overcome in the present invention by a construction which eliminates the possibility of the lock being set when the door is in a position wherein the rod might be projected exteriorly of the track.

A further object of the invention is to provide an overhead door locking mechanism wherein the parts are arranged for easy connection, facilitating assembly and mounting of the locking mechanism on a door and adjustments thereof to compensate for warpage or uneven surfaces, the connections being easily disengaged to facilitate repairs, replacements and adjustments.

A further object of the invention is to provide an overhead door locking mechanism which is of very simple construction, is strong and durable, is simple, and efficient in operation, which eliminates hazards attendant to improper operation, and which is well adapted for the purposes described.

With the above and other objects in view, the invention consists of the improved overhead door and affiliated locking mechanism, and its parts and combinations as set forth in the claims, and all equivalents thereof.

In the accompanying drawings in which the same reference characters indicate the same parts in all of the views:

Fig. 1 is a rear or elevational view of a portion of an overhead door in its closed position, showing the affiliated locking mechanism, portions of the supporting structure being shown in section;

Fig. 2 is an enlarged fragmentary detail view of an inner-face portion of the door showing the locking mechanism applied thereto with the lock in its released position;

Fig. 3 is a sectional view taken on line 3—3 of Fig. 2;

Fig. 4 is a similar sectional view, only showing the locking mechanism in its engaged or locking position;

Fig. 5 is an enlarged fragmentary detail sectional view taken on line 5—5 of Fig. 1;

Fig. 6 is a fragmentary detail sectional view taken on line 6—6 of Fig. 5;

Fig. 7 is an enlarged fragmentary detail view showing the releasable universal joint connection

between several of the locking mechanism members; and

Fig. 8 is a sectional view taken on line 8—8 of Fig. 7.

Referring now more particularly to the drawings, the complete sectional overhead door 15 is illustrated as having four sections, 16, 17, 18 and 19, but in actual practice, the door may include any number of sections. The sections 16, 17, 18 and 19 are hinged together in superimposed relation by hinges 20, preferably disposed adjacent both side margins of the sections. For the purpose of guiding the door to and from its overhead position, there is provided adjacent each side of the door a metal track 21 of channelled formation and comprising an upright section 22, and overhead horizontal section 23, and a curved section connecting the other sections.

The mechanism for guiding the door to and from its overhead position, except insofar as it is associated with the improved locking mechanism with which the present invention is especially concerned, will not be described in detail, as it forms the subject matter of my co-pending application, Ser. No. 525,320, now Patent No. 2,375,837, dated May 15, 1945. The door guiding mechanism is, however, of the type which requires a minimum of head room when the door is in its overhead position. To that end, the upright sections 22 of the tracks 21 terminate below the upper edge of the closed door so that the curved sections of the tracks curve upwardly and inwardly from the lower portions of the upper section 19 of the door. Guide rollers 25 for said upper door section are, therefore, carried by hinged plates 26 mounted on the upper section 19, with said guide rollers being engaged in and adapted to follow the curved and horizontal sections of the track 21. The arrangement of the roller-carrying plates is such that the projection of the rollers relative to the plane of the door section 19 is variable to compensate for differences in the proximity of the face of said door section to the tracks in different positions of the door. Below the upper section 19 all of the hinges 20 disposed on the side margins of the door sections have journalled therein shafts 27 and 27' carrying guide rollers 28 which ride in the tracks 21. A hinge 20 between a selected pair of intermediate sections of the door, as the sections 17 and 18, is modified somewhat from the other hinges in respect to the roller-carrying shaft 27' thereof, said shaft 27' being tubular with the bore thereof registering with an opening in the roller 28 carried by said shaft, whereby said tubular shaft 27' serves as a guiding housing for a reciprocatable locking rod 29 as will hereinafter appear.

Mounted through one of the intermediate sections of the composite door 15 and at a convenient elevation from the ground is a lock barrel 30 in which, as is customary, tumblers are adapted to be actuated by a key inserted into the barrel from exteriorly of the door. Turning the key and tumblers controlled thereby is effective to turn a lock projection or lug 31 which lodges within a recess 32 therefor in a vertical locking bar 33. Hence, turning movement of the lug 31 in the proper direction, through the engagement of said lug with the bar 33, lifts the bar. The bar is slidably mounted in a bracket 34 on the inner face of the door. As will appear hereinafter, and as is shown in Figs. 3 and 4, when the bar 33 is in its lifted position the latching mechanism, to be described, is released, while

when said bar is in its lowered position, the latching mechanism is held or locked in its engaged position of Fig. 4.

The latch mechanism comprises a bell crank lever 35 of bifurcated formation and pivotally mounted as at 36 on the inner face of the door, in a position to pivot in a horizontal plane, and immediately below the vertical locking bar 33. The bell crank lever is adapted to be rocked by a horizontally disposed plunger bar 37. The plunger bar is slidably mounted through the door section so as to project outwardly of both faces thereof. Plates on the opposite faces of the door section have inturned stamped flanges 38 which enter the bore in the door section through which the plunger is passed and form bearings for the bar plunger to relieve wear on the stock of the door section. The inner end of the plunger bar 37 is embraced by inner arm portions of the bell crank lever 35 and is formed with projecting transverse pin portions 39 engaged within slots 40 in said bell crank lever. The free ends of the other arms of the bell crank lever have pivotally attached thereto the inner end of a bifurcated, angularly shaped link 41. The outer end portions of the link 41 are crimped and have tightly secured therebetween the offset outer end portion of a horizontally disposed operating strap or connection 42. The opposite end of said strap or connection 42 is forked and hooked, as at 42'. The hooked extremity 42' of said strap 42 is of considerable importance in respect to the manner in which it releasably and universally adjustably engages the end portion of the reciprocatable locking rod 29. As will appear most clearly from Figs. 7 and 8, said locking rod 29, slightly inwardly of its inner end is formed with opposite plain surfaced grooves 43 which form with the rod enlargement therebeyond opposed shoulders 44. The reduced portion of the rod 29, formed by the recesses 43, is of a dimension to fit within the slotted opening in the extremity 42' of the connection 42. Thus, by disposing the member 42 angularly in the manner shown in broken lines in Fig. 7, the hooked extremity 42' of the member 42 may be engaged with the slotted and shouldered portion of the rod 29, whereupon the member 42 is then turned horizontally and is effectively hooked with the end portion of the rod 29. Turning or angular movements of the connected members 29 and 42 is permitted, and the arrangement described is especially desirable and advantageous in installing the mechanism on a door. It is also obvious that said parts may be readily disconnected for repairs, replacements or adjustments, and the universal movement permitted as between said connected elements adapts the arrangement for easy installation regardless of uneven surfaces or warpage.

It should be observed that in addition to being guided by the tubular portion 27' of the hinge 20, the reciprocatable locking rod 29 has another portion thereof guidingly supported by the outwardly directed flange of a bracket 45 mounted on an inner-face portion of the door. A coiled spring 46 surrounds the portion of the rod 29 between the flange of the bracket 45 and the hooked extremity 42' of the connection 42, being confined, as shown, and placing the composite connection 29—42 under tension when the same is reciprocated for a locking projection of the rod 29, as in Fig. 4.

The outer vertical flange of the vertical section 22 of a track 21 has an aperture or open-

ing 47 therein in registration with the rod 29. Said aperture is only slightly larger than the diameter of the rod 29 so that there will be a minimum of play as between the rod and the aperture when the rod is projected through the aperture. The latter may only be accomplished when the overhead door is in its closed vertical position, and it is desired to latch, or latch and lock the door. Then, the mechanism is operated to project the connection 42 and engaged rod 29 to the left, relative to the drawings, whereupon the parts will move from the position of Figs. 2 and 3 to the position of Fig. 4, projecting an end portion of the rod 29 through the aperture 47 in the anchored track 21. When this is accomplished, not only is the entire composite door latched against vertical movement, but, by virtue of the close fit as between the rod 29 and the aperture 47, there is a minimum of play and consequently no vertical movement of any consequence may be imparted to the door such as might be sufficient to cause the guide rollers 25 for the upper door section 19 to move into a portion of the track which might permit undesirable inward swinging movement of the upper door section 19. The reciprocation of the composite element 42-29 is accomplished through a single operation transmitted by the bell crank lever 35, the link 41, and the connection 42, all previously described. The control and operation of the latching mechanism is accomplished from exteriorly of the building through the simple expedient of pushing the plunger bar 37. If it is desired to manipulate the latching mechanism from interiorly of the building, this can readily be accomplished by manually swinging the bell crank lever 35.

Operation of the latching mechanism can only be accomplished when the vertical locking bar 33, previously referred to, is in its raised position. When the latching mechanism is engaged and the locking bar 33 is in its depressed position, the free lower end of said bar engages in a slot 48 in the plunger bar 37, thereby holding the plunger bar in its innermost position. When the locking bar 33 is reciprocated upwardly, the slot 48 is disengaged, thereby freeing the parts for movement, and permitting reverse swinging movement of the bell crank lever 35 and associated connections to accomplish a withdrawal of the latching rod 29 from the track aperture 47. The movement of the parts in the last stated direction is facilitated by expansion of the coiled spring 46.

As was mentioned, reciprocations of the locking bar 33 in the proper direction to accomplish locking and unlocking of the mechanism is accomplished from exteriorly of the door by the key operated tumblers in the barrel 30, and from interiorly of the building, the locking bar may be lowered or raised by manually engaging the flanged upper extremity thereof.

The improved overhead door latching and locking mechanism entails a minimum of parts which may be easily assembled, installed and adjusted. The tubular shaft 27, mounted on the hinge 20, forms a protective sleeve for a portion of the reciprocatable rod 29. The outer end of said rod, which may for locking purposes be projected through the roller 28, is always housed within the channel of the track 21. The latching mechanism may not be operated to project the rod 29 unless the same is in alignment with the track aperture 47, and this occurs only when the door is in its lowered, closed position. There-

fore, there is no possibility of improper operation of the latching mechanism at a time when the door is partially open and nothing can occur in this respect which might wedge or deflect the parts. The invention furthermore provides efficient and easily operated mechanism for positively latching, or latching and locking, the door. The mechanism has a minimum of projecting parts and will not adversely affect the overhead room required by the door when open.

While the latching mechanism has been shown and described as extending from a central portion of the door outwardly to only one side thereof for latching engagement with the track along one margin of the door, it is obvious and it is within the scope of the present invention that the latching mechanism may be duplicated for the other margin of the door so that sets of latching rods and connections, extending in opposite directions from the central operating plunger, be simultaneously actuated thereby. The overhead door latching and locking mechanism is of simple and novel construction and is well adapted for the purposes described.

The improved latching and locking mechanism is not to be limited to incorporation in connection with the particular type of door and guiding mechanism shown and described because the improvement is susceptible of more general application and all embodiments are contemplated as may come within the scope of the claims.

What is claimed as the invention is:

1. Fastening means for an overhead door of the type which includes a plurality of sections hinged together in superimposed relation to fit in a door frame with tracks adjacent the sides of the door frame and bearings on the door sections engaging the tracks to guide the door sections into and out of the frame, one of the bearings being tubular and the track adjacent said tubular bearing when the door is in closed position within the frame being formed with an aligned socket, comprising a latching bar reciprocatably mounted in said tubular bearing and projectable into said track socket only in the closed position of the door, manual control means for the latch mounted on the door remote from said socket, and a jointed linkage directly connecting said control means to the latching bar.

2. Fastening means for an overhead door of the type which includes a plurality of sections hinged together in superimposed relation to fit in a door frame with tracks adjacent the sides of the door frame and bearings on the door sections engaging the tracks to guide the door sections into and out of the frame, one of the bearings being tubular and the track adjacent said tubular bearing when the door is in closed position within the frame being formed with an aligned socket, comprising a latching bar reciprocatably mounted in said tubular bearing and projectable into said track socket only in the closed position of the door, manual control means for the latch mounted on the door remote from said socket, and a jointed linkage extending in a rectilinear direction relative to the bar and connecting said control means to the latching bar, the connection between said linkage and the latching bar being disengageable and universally adjustable.

3. Fastening means for a door adapted to move relative to a door frame with a socket associated with the frame adjacent a peripheral portion of the door when the latter is in closed position within the frame, comprising a latching

bar reciprocably carried by the door and projectable into said socket only in the closed position of the door, manual control means mounted on an intermediate portion of the door, and a link member connected at one end with said manual control means and disengageably and universally adjustably connected at its other end with said latching bar.

4. A fastening means for an overhead door of the type which includes a plurality of sections hinged together in superimposed relation to fit in a door frame with tracks adjacent the sides of the door frame and bearings on the door sections engaging the tracks to guide the door sections into and out of the frame, one of the bearings being tubular and the track adjacent said tubular bearing when the door is in closed position within the frame being formed with an alined socket, comprising an elongated latching rod reciprocatably mounted in said tubular bearing and arranged for projection beyond the door margin and into said track socket to latch the door when it is in closed position, the inner end portion of said rod being recessed and shouldered, a lever pivotally mounted on the door remote from said tubular bearing, means accessible from a face of the door for moving said lever, and a link connecting the lever with the inner end of the rod, the rod engaging end of the link being formed with a hook-shaped fork releasably engaging the recessed and shouldered end of the rod and universally adjustable with respect thereto.

5. A fastening means for an overhead door of the type which includes a plurality of sections hinged together in superimposed relation to fit in a door frame with tracks adjacent the sides of the door frame and bearings on the door sections engaging the tracks to guide the door sections into and out of the frame, one of the bearings being tubular and the track adjacent said tubular bearing when the door is in closed position within the frame being formed with an alined socket, comprising an elongated latching rod reciprocatably mounted in said tubular bearing and arranged for projection beyond the door margin and into said track socket to latch the door when it is in closed position, the inner end portion of said rod being recessed and shouldered, a lever pivotally mounted on the door remote from said tubular bearing, means accessible from a face of the door for moving said lever, a link connecting the lever with the inner end of the rod, the rod engaging end of the link being formed with a hook-shaped fork releasably engaging the recessed and shouldered end of the rod and universally adjustable with respect thereto, and a confined coiled spring associated with the inner end portion of the rod and bearing against the forked end of said link to resiliently hold it in engagement with the shouldered end of the rod and to yieldingly oppose projection of the rod and connected link.

CHRIST BUEHNER.
